UNITED STATES PATENT OFFICE.

ROBERT L. ROYSE, OF MARTINSVILLE, INDIANA.

AMALGAMATOR-RIFFLE.

1,013,066.

Specification of Letters Patent. Patented Dec. 26, 1911.

Application filed May 16, 1911. Serial No. 627,527.

To all whom it may concern:

Be it known that I, ROBERT L. ROYSE, a citizen of the United States, residing at Martinsville, in the county of Morgan and 5 State of Indiana, have invented certain new and useful Improvements in Amalgamator-Riffles, of which the following is a specification.

This invention relates to amalgamator 10 riffles, and one of the principal objects of the invention is to provide a series of zigzag mercury-coated riffle plates designed to be placed in a sluicebox to catch small particles of gold, or other values amenable to amalgamation, as the water or slime passes from 15 the amalgamator and is led off through the sluicebox to the refuse or tailings dump.

Another object of the invention is to divide up the current of slime as it passes 20 through the sluicebox into a number of small currents which are compelled to take a zigzag course so that all the slime or water is brought into contact with one or the other of the plates as it passes through the sluicebox, thus attracting all the values to the 25 mercury-coated plates.

Still another object of the invention is to provide simple and cheaply constructed 30 zigzag riffle plates which can be readily removed from and replaced in the sluicebox and which will save a large percentage of the floating values which in great part have heretofore been run off with the tailings.

These and other objects may be attained 35 by means of the construction illustrated in the accompanying drawings, in which,

Figure 1 is a plan view of a portion of a sluicebox containing amalgamator riffles made in accordance with this invention; 40 Fig. 2 is a side elevation of the same; Fig. 3 is a transverse section on the line 3—3 of Fig. 1 looking in the direction indicated by the arrows.

Referring to the drawings, the numeral 45 1 designates a sluicebox which may be of the usual or any suitable construction. Placed within the sluicebox is a series of riffle plates, which series is connected together by bolts and spacing collars, as will 50 be now described. The plates 2 are of zig-

zag form as shown, and at the end of each plate is a straight flange or foot 3. Each of these plates is coated with mercury and in order that the plates may be held the required distance apart, a bolt 4 is passed 55 through alining perforations in the foot 3 at a point near the center of its width and between each pair of plates is a collar or sleeve 5, which holds the plates the required distance apart. It will be obvious that any 60 number of these plates may be utilized and that the plates may be of any required length. However, it is deemed expedient to make the plates of such length that they can be readily handled or removed from the 65 sluicebox, and thus any number of series of plates may be placed in the box, one after the other, in longitudinal series, in order to insure contact of every portion of the 70 water or slime as it passes toward the discharge end of the sluicebox.

Upon reference to Fig. 3 of the drawing, it will be seen that the riffles extend slightly above the upper edge of the sluicebox to prevent splashing or running over of the 75 slime.

From the foregoing it will be obvious that this invention is exceedingly useful in all classes of placer or free milling plants, and that the cost of production and maintenance 80 is very slight when compared with the saving of values by its use.

I claim:

In combination, a sluice, an amalgamating element resting upon the bottom thereof, 85 and comprising a series of longitudinally disposed, upstanding parallel plates corrugated to form zig-zag channels longitudinally of the sluice, said plates extending above the normal liquid level in the sluice, 90 and means for fastening and holding said plates in spaced relation and adapting the same for removal and re-setting.

In testimony whereof I affix my signature in presence of two witnesses.

ROBERT L. ROYSE.
